CLAIM

The ornamental design for a portable cloth-surface cleaner, as shown and described.

DESCRIPTION

FIG. 1 is a top perspective view of a portable cloth-surface cleaner showing my new design;

FIG. 2 is a front elevational view thereof, the opposite side being a mirror image;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is another top perspective view thereof showing the new design in a closed status.

FIG. 1

FIG. 7

FIG. 2

FIG. 3

FIG. 4

FIG. 5

FIG. 6
